UNITED STATES PATENT OFFICE.

WILLIAM D. FORSYTH, OF YOUNGSTOWN, OHIO.

BRAKE-BEAM.

996,632.

Specification of Letters Patent.

Patented July 4, 1911.

Application filed November 2, 1910. Serial No. 590,297.

To all whom it may concern:

Be it known that I, WILLIAM D. FORSYTH, a citizen of the United States, and a resident of Youngstown, in the county of Mahoning and State of Ohio, have invented a new and useful Brake-Beam, of which the following is a specification.

This invention relates to beams for supporting the brake-shoes of railway cars, and 10 its object is to provide a strong trussed brake-beam at minimum cost of construction.

In the accompanying drawing, Figure 1 is an elevation of a properly rolled bar showing 15 the slits to permit expanding the same. Fig. 2 is a plan of the completed brake-beam. Fig. 3 is an end view of the beam before the strut or head is inserted. Fig. 4 is a cross section on the line 4—4 of Fig. 2, on a larger 20 scale. Fig. 5 is a plan on a larger scale of the strut or head. Fig. 6 is a cross section on a larger scale on the line 6—6 of Fig. 1.

Similar reference characters refer to like parts throughout the several views.

The brake-beam shown in the drawings is formed from a properly rolled bar, shown 25 in Fig. 1, having ribs 5 and 10, by slitting the same along the lines 7 and 8, thus leaving a beam 9 having a central rib 5, and two 30 side members 11. The middle portions of these side members are then pressed out laterally and inwardly as shown in Fig. 8, forming a double truss of which these members 11 form the tension members and the 35 beam 9 the longitudinal compression member. The tension members 11 are stretched by this process, which may be carried out when the rolled bar is cold or after it is heated. A head or strut 12 having a central 40 web 13 provided with a hole 14 to receive the brake-lever, exterior flanges 15, 16 and 17, and a middle rib 18 adapted to extend between the members 11, is then driven in between the tension members 11 and the 45 beam 9. The resultant construction has great strength for its weight as the members 11 and 9 are integrally connected at their

ends and the head or strut 12 holds the members in proper relative positions. The head may be of any desired material, such 50 as cast-iron, cast-steel or malleable cast-iron, while the bar from which the beam proper is formed is preferably of mild steel.

The proportions and sizes of the parts may be varied to suit the different requirements.

Having now explained my construction, what I claim as my invention and desire to secure by Letters Patent is:—

1. A brake-beam comprising a central longitudinal compression member having an exterior rib, side tension members having their ends integral therewith and extending therefrom at an angle and also toward each other to form the tension members of a truss, 65 and a head between said members having flanges engaging the sides of the longitudinal compression and tension members.

2. A brake-beam comprising a central longitudinal compression member and two tension members integrally connected at their 70 ends to the sides of the ends of the central member and forming acute angles therewith and with each other, and a head forming a strut between said members and having a central opening and side flanges fitting both 75 edges of each of the tension members and the compression member.

3. A brake-beam formed of a bar of metal slit longitudinally intermediate its ends and 80 having a plurality of its divided portions spread apart from a main portion, in combination with a metal head forming a strut interposed between the spread portions of the bar and having flanges to prevent all 85 lateral displacements of the portions of the bar.

In testimony whereof I have hereunto signed my name in the presence of two subscribing witnesses:

WILLIAM D. FORSYTH.
